DESIGN FOR A DESK OR ANALOGOUS ARTICLE

James R. Jones, Lakewood, and Carl L. Elofson, Jamestown, N. Y., assignors to Art Metal Construction Company, Jamestown, N. Y.

Application March 10, 1944, Serial No. 112,849
Term of patent 14 years

(Cl. D33—7)

To all whom it may concern:

Be it known that we, James R. Jones and Carl L. Elofson, citizens of the United States, residing respectively at Lakewood and Jamestown, in the county of Chautauqua and State of New York, have invented a new, original, and ornamental Design for a Desk or Analogous Article, of which the following is a specification, reference being had to the accompanying drawings, forming a part thereof.

In the drawings:

Fig. 1 is a front perspective view of a desk embodying our new design.

Fig. 2 is an elevational view of one end of the desk.

Fig. 3 is a rear perspective view of the desk.

Fig. 4 is an elevational view of the other end of the desk.

The dominant features of the design reside in those portions shown by solid lines in the drawings.

We claim:

The ornamental design for a desk or analogous article, substantially as shown and described.

JAMES R. JONES.
CARL L. ELOFSON.
